UNITED STATES PATENT OFFICE.

WILLIAM H. TROWBRIDGE, OF GEORGETOWN, KENTUCKY.

TOBACCO PRESS.

Application filed December 5, 1927. Serial No. 237,843.

This invention relates to tobacco presses, and has more particular reference to an improved press for flattening tobacco leaves to improve their appearance and for pressing a 5 large quantity of the same into compact form so as to require a minimum amount of space in storage or during shipment.

The primary object of the present invention is to provide a press of the above kind 10 which is extremely simple and durable in construction as well as efficient and reliable in operation.

A still further object is to provide a tobacco press embodying a packing box or 15 press chamber having a pressing board or follower slidably mounted therein, and simple and efficient manually operable means for effecting movement of the packing board to compress the tobacco between the latter and an end of the packing box.

Other objects will appear as the nature of the invention is better understood, and the same consists in the novel form, combination and arrangement of parts hereinafter more 25 fully described, shown in the accompanying drawings and claimed.

In the drawings, wherein like reference characters indicate corresponding parts throughout the several views,

Figure 1 is a side elevational view, partly broken away, of a tobacco press constructed in accordance with the present invention;

Figure 2 is an end elevational view looking toward the right of Figure 1;

Figure 3 is a vertical transverse section taken upon line 3—3 of Figure 1;

Figure 4 is an elevational view of the windlass mechanism effecting movement of the pressing board or follower as seen looking toward the left of Figure 1;

Figure 5 is a fragmentary plan view showing the connection between the pull bar of the pressing board and the cable of the winding drum or windlass mechanism;

Figure 6 is a transverse vertical sectional view taken upon line 6—6 of Figure 1;

Figure 7 is a transverse section taken upon line 7—7 of Figure 1; and

Figure 8 is an enlarged elevational view of the pressing plate and the pull bar thereof.

Referring more in detail to the drawings, the present press includes a horizontally elongated open top press box 5 having its inner end closed by a suitably braced end wall 6 and provided upon the upper longitudinal edges of the side walls thereof with

slide rails 7. The side walls of the press box are preferably formed of a plurality of boards superimposed in edge to edge relation as shown in Figures 1, 6 and suitably secured to upright posts or stanchions 8 disposed at suitable intervals at the outside thereof. The side walls are also rigidly connected at intervals by cross bars 9 which extend outwardly of the side walls of the press box and to the outer ends of which are secured the lower ends of inclined braces 10 that extend upwardly and inwardly and are fastened to the adjacent posts 8 by bolting or the like. Extending longitudinally of the side walls of the press box 5 upon the inner faces thereof and in horizontal alinement are guide ribs 11 which engage in side notches 12 of a vertical follower or press board 13 whereby the latter is supported for horizontal sliding movement within the press box. In order to further support the press board for sliding movement and to guard against such longitudinal tilting thereof as will cause objectionable binding, said press board or follower plate 13 is provided at its top with a cross bar 14 whose projecting ends are arranged to ride upon the slide rails 7.

The end wall 6 is preferably composed of three vertical boards as shown in Figure 3, 85 said boards being connected by cross bars 15 whose ends project and are fastened to the adjacent ends of the side walls of the press box as at 16. The central board of the end wall 6 has an upper end portion which projects above the upper ends of the remaining boards and is bifurcated to provide a guide slot 17 through which slidably extends a pull bar 18 having its outer end rigidly connected to the top of the pressing board or 90 follower 13 as shown clearly in Figures 1, 2 and 8. For this purpose, the pull bar 18 is preferably bolted to the top of the follower as at 19 at a point inwardly of the outer end of the pull bar and an inclined brace 20 95 is provided between the outer side and lower end portion of the follower 13 and the outer end of the pull bar. In this way the follower board proper is effectively braced against outward pressure such as occurs 100 when the follower is slid toward the inner end of the press box for compressing the tobacco leaves suitably supported in vertical position between said follower and the inner end wall 6 of the press box.

For exerting an inward pull upon the pull bar 18 a windlass mechanism is preferably

provided which is manually operated and includes a pair of spaced vertical posts 21 suitably rigidly mounted in spaced relation to and inwardly of the inner end of the press box as shown in Figure 1. The windlass mechanism specifically includes a winding drum 22 rotatably mounted upon a horizontal axis or spindle having its ends journaled in bearing brackets 23 fixed to the respective posts 21 at the inner sides of the latter. The winding drum 22 is provided with a plurality of radiating or radial handles or levers 24 so that the drum may be readily manually turned for winding the cable 25 thereon to exert an inward pull upon the pull bar 18, one end of the cable 25 being suitably secured to the drum 22 and the other end thereof being detachably connected to the inner end of the pull bar 18 as shown in Figures 1 and 5. In order to releasably hold the drum 22 against turning and thereby retain the cable 25 wound thereon, a vertically swinging latch bar 26 is pivoted at one end to one of the posts 21 and is adapted to be swung downwardly to a horizontal position behind a keeper 27 fixed to the other post 21 so as to be disposed in the path of the outer end of the lever or handle 24 which is adjacent and inwardly of said latch bar. Obviously, by slightly raising the latch bar 26 the drum may be partly turned to cause the next proceeding handle 24 to pass the latch bar after which the latter may be again lowered to retain the tobacco in the press box under the compression which has thereby been effected.

As shown in Figures 1 and 5, the free end of the rope or cable 25 preferably has a hook 28 attached thereto and the inner end of the pull bar 18 has a transverse slot 29 in which the hooked end of the hook 28 may be engaged. A bolt 30 extends vertically through the inner end of the pull bar 18 so as to intersect the slot 29 and so that the hook 28 may be engaged therewith. Thus, upon engaging the hooked end of the hook 28 in the slot 29 the bolt 30 may be inserted to securely retain the hook connected to the pull bar 18. On the other hand, removal of the bolt 30 will be required in order to effect disengagement of the hook 28 from the pull bar.

In operation, the press board or follower 13 is slid to a point adjacent the outer end of the press box and the tobacco leaves are suitably suspended in a vertical position

within the press box between the follower 13 and the inner end wall 6 of the press box. The latch bar 26 is then swung out of the path of the handles 24 and the cable 25 is unwound from the drum 22 so that the hook 28 may be connected to the pull bar 18 as shown in Figure 1. The drum 22 is then manually turned by use of the handles 24 in a clockwise direction as shown in Figure 1 so as to cause the cable 25 to be wound on said drum and effect inward sliding movement of the follower 13. When this takes place, the suspended leaves are flattened and pressed into compact relation so that a considerable bulk of the leaves may be pressed into flat neat appearing form and in such relation as to require a minimum amount of space when in storage or during shipment. The guiding of the pull bar 18 in the slot 17 effectively prevents lateral twisting of the follower 13 about a vertical axis such as would cause binding of the same against the sides of the press box. When the device is not in use, the hook 28 may be readily disconnected from the pull bar 18 and the press structure proper embodying the press box and follower may be placed aside at any point desired.

From the foregoing description it will be seen that I have provided a simple and durable tobacco press which is thoroughly reliable in operation and into and out of the press box of which the tobacco may be readily placed or removed.

Minor changes may be made without departing from the spirit and scope of the invention as claimed.

What I claim as new is:

In a tobacco press, a horizontal press box, a pressing board slidably mounted in said press box and movable toward an end of the latter to press the tobacco, a pull bar rigidly connected to the top of said pressing board, and a windlass mechanism for exerting a pull on said pull bar including a pair of posts having a winding drum journaled thereon, said drum having radial handles, movable between the posts, a keeper on one post, a latch bar pivoted to the other post and movable into the path of the handles when engaged with the keeper, a cable attached to the drum, and means to detachably connect the cable to the pull bar.

In testimony whereof I affix my signature.
WILLIAM H. TROWERIDGE.
